UNITED STATES PATENT OFFICE.

JAMES HOUGH, OF GUELPH, CANADA.

PRINTING-MACHINE.

No. 799,648.

Specification of Letters Patent.

Patented Sept. 19, 1905.

Application filed April 13, 1904. Serial No. 203,055.

To all whom it may concern:

Be it known that I, JAMES HOUGH, of the city of Guelph, in the county of Wellington, in the Province of Ontario, Canada, have invented certain new and useful Improvements in Printing-Machines, of which the following is a specification:

My invention relates to improvements in printing-machines; and the object of the invention is to devise a machine whereby matter of all kinds in large or small type, and particularly such large type as is used for address-cards, announcements, newspaper-bulletins, price-tickets, packing-case addresses, &c, and generally all such printing as is done on flat surfaces, may be printed expeditiously and with the letters accurately spaced according to their widths; and it consists, essentially, of a suitable frame, an adjustable platen supported in the frame, a type-carriage, a guiding-frame on which the same is laterally adjusted, and guideways on which such frame has longitudinal movement, a rotatable disk provided with a circle or circles of stems carrying at the bottom the type, and a supporting-base having a slot through which the type is designed to print, and an internal inking-pad, a lever pivoted on the back of the carriage-frame, and a plunger designed to be operated thereby to depress the type-stems one at a time to print through the slot, a ratchet-feed mechanism located at the back of the carriage and operated by the depression of the lever to feed the carriage laterally, and consequently the slot through which the printing is done, a determinate distance commensurate with the width of the letter, the various parts being otherwise arranged and constructed in detail, as hereinafter more particularly explained.

Figure 1 is a perspective view of my improved printing-machine. Fig. 2 is a perspective view from the back of the machine, showing the feeding mechanism, the rotatable disk being removed from the circular base. Fig. 3 is a longitudinal section through the machine on a plane passing through the center of the rotatable disk. Fig. 4 is a cross-section on a plane passing through the center of the rotatable disk. Fig. 5 is a plan view of the rotatable disk, showing the arrangement of the type-stems and indicating-letters of the same and carriage. Fig. 6 is a view of the rotatable disk reversed. Fig. 7 is an enlarged detail showing the mechanism connected to the operating-lever for operating

the letter-spacing ratchet on the ratchet-bar. Fig. 8 is a detail of the device for shifting the plate or base carrying the rotatable disk.

In the drawings like characters of reference 60 indicate corresponding parts in each figure.

A are the ends of the machine, which are suitably connected together by the front cross-rods, back cross-bar a' , and the lower central cross-bar a'' .

A' is a platen which extends at the end into suitable guideways in the frame and has the central and end depending lugs A^2 and A^3 , respectively.

2 and 3 are stems which extend from the central lugs A^2 and A^3 , respectively, through the cross-bar a'' . The stem 2 has a spiral spring $2'$ encircling the same between the lug A^2 and the bar a'' . The stems 3 have spiral springs $3'$ encircling the same and extending between the lugs A^3 and the bar a'' . The central stem is threaded and has located at the bottom end thereof the hand-wheel 2^2 . It will now be seen that the platen A' is resiliently supported and may be adjustable vertically by means of the hand-wheel 2^2 .

B is a roll of paper, the spindle of which is supported in suitable bearings in the frame, as indicated, and the paper on the roll of which passes through openings and over the platen A' to the back of the machine, whence it passes between the rubber rolls b'' , located toward each end of the feed-spindles b^2 and b^3 , respectively. The feed-spindle b^3 is provided with a hand-wheel b^4 .

B' is a shearing-knife which is pivoted on a pin B^2 and is provided with a handle B^3 , by which it is raised on the pivot-pin.

B'' is a spring encircling the pin B^2 , having one end fastened to the frame and the other end extending underneath the pin b^4 on the knife.

To cut off the paper, it is merely necessary to raise the knife B' and draw the paper out substantially horizontally, when the knife may 100 be brought down against the edge of the bar a' , and thereby sever the paper completely across.

a^3 represents guide-rails formed on the top of the sides A of the frame. One of the rails 105 is provided, preferably, with equidistant notches a^4 .

C is a supplemental frame rectangular in form and having the ends thereof resting on the guide-rails a^3 and provided with lip-handles C' , whereby the frame and the carriage 110 supported thereon, as will hereinafter appear,

may be raised and placed in any desired position upon a table, box, or floor. C² is a dog-lever pivoted on a pin c⁰ on the top of the frame C, such dog being held in engagement with one of the notches d⁴ by spiral springs e⁵ encircling the pin and attached to the dog in the usual manner. The frame C is also provided at the front with a lip-handle c³ in order to adjust it. The interiors of the front and back of the frame C are provided with grooves c and c'. The groove c is provided with two upwardly-extending cut-away notches c² c', as indicated.

D is the carriage-frame, which is rectangular at the base and is provided at the front with tongues d, which fit and are designed to move laterally within the groove c. The tongues d are approximately the same width or slightly less than the notches c² and are of the same distance apart, so that when these tongues are directly under the notches by lifting the carriage the tongues will pass out of the groove c and the carriage removed.

d' is a divided tongue formed on the back 25 of the carriage-frame and fitting in the back groove c'. The tongue d' is divided or cut away opposite the center of the back of the carriage, as indicated and for a purpose which will hereinafter appear.

30 The carriage D is designed to be moved laterally, as will hereinafter appear, with the tongues d and d' in their respective guideways c and c', and when the tongues d are brought opposite the openings or notches c² the carriage may be removed by raising the forward end thereof and bringing the tongues d through the notches and then drawing forwardly on the carriage so as to relieve the back tongue d' from the groove c'.

40 c³ is a ratchet-rack formed on the rear bar of the frame C.

4 is a stop adjustably extending through a post 5, secured in the back bar of the frame C and held securely by a binding-screw 6.

45 The stop 4 is toward one end of the back bar of the frame C, and toward the other end I provide a similar stop 4', which is held in position in the same way.

The frame D is provided with an upwardly-extending rear portion D', at the center of which is formed a vertically-disposed bearing d², through which extends the rod d³.

E is a plate, through which the rod d³ extends, such plate being provided with end 55 notches e, into which extend the T-shaped ends of the springs e', which are suitably held at the opposite end on the upwardly-extending portion D' of the carriage. The plate E is supported on the rod d³ (see Figs. 4 and 7) 60 by a cross-pin d⁴.

F is a pawl pivoted on a pin f at the bottom of the rod d³. The pawl is designed to engage with the ratchet c³ on the inside of the back of the frame C.

65 G is a plate connected to the center of the

upwardly-extending portion D' of the carriage-frame by the screws g, extending through slots g' in the plate. The plate G has a right-angular projection g² at one end, designed to come in contact with the stops 4 7c and 4', and the lower right-angular projection g³, which extends underneath the pawl F.

H is a supporting-plate for the rotatable disk I, such plate being provided with an external face-rim h and an internal face-rim h', 75 between which is situated the inking-pad H'. The plate H has laterally-extending lugs h² and h³ at each side, which extend and are slidably supported on the frame D by the inwardly-extending ribs d^{1x}, forming portion of the 80 side bars of the frame D. The plate H has also a forwardly-extending portion H², which extends to the inside of the standard D², forming portion of the carriage-frame.

D³ is a bell-crank pivoted on a pin 7, secured in the standard D². The lower end of the bell-crank engages with the projection H².

8 is a catch pivoted on the pin 8' in the standard and located in the slot D⁴ in the standard D². The catch 8 has a pointed projection 8² at the front lower end, the forward movement of which is limited by the stop-pin 8³, extending through the standard D² above the pivot-pin 8'.

9 is a spring which is spirally wound 95 around the pivot-pin 8' and extends to the front of the upper end of the catch and is connected at the lower end to a pin 9'. It will now be seen that the normal tendency of the spring 9 is to force the pointed projection 8² 100 into the forward position. The front end of the bell-crank D³, however, is broad, so as to extend over the top of the pointed projection 8².

10 is a spiral spring connected at one end 105 to the front of the carriage-frame and at the other end to the plate H.

H³ is a slot made in the back end of the plate H and extending between the rims h and h'.

H⁴ is a circular plate which fits within the rim h' and through which extends the screw-plug 11, which is provided with a notched enlarged head 11', designed to be normally covered by the ornamental depressing-cap 11², 115 which I utilize to depress the type-stem disk, so as to ink the type without shifting the type-carriage. The screw-plug 11 extends into the center of the plate H, the head 11' serving to limit the upward movement of the circular plate H⁴. The plate H⁴ is resiliently supported by the helical spring 12, surrounding the plug 11.

I is the rotatable plate, which has attached to or forming part of the same the rim I', to 125 which is secured at the bottom the circular plate I². The plates I and I² are secured together at the center by a sleeve i, surrounding the head of the plug 11.

J represents the outer circle of type-stems, 130

which extend through holes in the plates I and I² and are provided at the bottom with the type-plates j, on which are secured the types j', of rubber or any other suitable material. The type-stems J are preferably square in cross-section and provided with tapered upper ends j². Each type-stem is surrounded by a spiral spring j³, which serves to normally hold the type-stem in a raised position by pressing upon the bottom plate I', and a pin j⁴ extending through the type-stem.

J' represents the inner circle of type-stems, the type-plates and types of which are constructed in the same way as those attached to the type-stems J. The type-stems J' are also resiliently supported in the same way. The types at the bottom of the type-stems J and J' extend over the inking-pad H'.

K and K' are the inner and outer indicating ring-plates for the inner and outer circle of type-stems, such ring-plates indicating at the point radially opposite each type-stem the particular letter of each type.

It will of course be understood to those familiar with printing that it is necessary to provide for the proper spacing of the letters, as some letters are wider than others, such, for instance, as the "W" or "M" being wider than the "I" or "N." To provide for the movement of the type-carriage commensurate with the width of each letter, so as to properly space the letters, I make the type-stems attached to the wider letters shorter than those attached to the narrower letters or characters in order to provide for less of a ratchet-feed, as will hereinafter appear.

L is the main operating-lever whereby the impression to the type is given. The lever L is provided with a handle l, and is substantially L-shaped in form, being pivoted on lugs L', attached to or forming part of the bracket L², secured to the upper carriage-frame D'.

M is a plunger which is provided with a reduced intermediate portion m and the bottom socket m'. The plunger M fits within the socket l' in the bracket L² and is held normally in the raised position against the lever by a spiral spring m², encircling the reduced portion of the plunger and extending between the bottom of the socket and the enlarged upper end of the plunger.

N represents a pair of bars pivotally connected to the lever L at the front end and having the depending back ends N' extending underneath the pin d⁴, passing through the rod d³. The bars N are provided with slots n and an adjustable fulcrum-pin n', which extends through the slots n into one or the other of the holes l³ in the bracket L², so as to provide a fulcrum for the bars N.

O is a double arm provided with a rearwardly-extending slotted projection o, through which extends the upper end of the rod d³.

o' is a spiral spring encircling the rod d³

and extending between the projection o and the plate E.

o' is a spiral spring encircling the rod d³ and extending between the bearing d² and the pawl F.

The arm O is pivoted at the sides on the pins o⁴, extending through the lugs d⁷, forming part of the carriage-frame.

O' represents bars located on the end of the double arm O and provided with inwardly-extending lips, as indicated. The bars O' are slotted and are connected to the ends of the arms O by the pins o⁵, extending through the slots. The lips on the bars O' are designed to extend over the rotatable disk I, and the bars O' are made slotted, so that the lips may be withdrawn from over the disk in order that it may be removed vertically.

It will now be seen on reference to Figs. 1 and 4 that by grasping the handle l and pressing down upon the lever L the socket m¹, the plunger M being above one of the outer circles of type-stems will depress such type-stem through the slot H³ of the plate H and imprint upon the paper on the platen a letter. The springs m², o', and e' will restore the lever to its normal position when released. The disk I may be then rotated by hand to bring the stem of any desired letter underneath the plunger M, when the same operation may be repeated, so as to form words or numbers, as desired.

It is essential that at the same time a letter is printed the type should be inked, and when the lever L is manipulated, as hereinbefore described, the back ends N' of the bars N extending underneath the pins d⁴ will as they are tilted on their pivot n' raise the rod d³ against the pressure of the springs o' and e' and thereby tilt through the medium of the spring o', extending underneath the projection o, the double arm O and bring the lips of the bars O' upon the edge of the rotatable disk or plate I, thereby holding it securely on the inking-pad during the period that the letter is being made by the type. Immediately, however, the lever is released and returns to its normal position the lips O' also release the disk and the spring 12 forces the type clear of the inking-pad, and thereby allows of the disk to be turned by hand. At the same time that the lever is depressed to raise the rod d³ the pawl F is raised at its point of pivotal connection with the rod d³, thereby dragging the point of the pawl over the ratchet-teeth c'. When the lever is released, the rod d³ being forced downwardly again serves to push the pawl to a substantially horizontal position, and necessarily in doing this must force the carriage D one

space in the direction indicated by arrow. The length of the space will depend upon the height to which the pivot end of the pawl is raised, and this height itself will depend on the distance that the lever is depressed. This

distance is regulated by the height of the stem of the type, so that if the stem is a long stem the lever gets a less depression and consequently the pawl less raise and the feed of the carriage is less. The longer stems are attached to the narrower letters, so that the space fed will be less to imprint a narrower letter. The short type-stems are attached to the broader letters so that the movement of the lever will be likewise increased and consequently the feed of the carriage increased and the space for the letter likewise increased to receive the broad letter. It will thus be seen that the movement of the carriage is regulated by the height of the stem attached to the type, so that the words may be formed with the letters the requisite distance from each other. It will of course be understood from what has been before described that all the type after being inked will be raised from the inking-pad by means of the helical spring 12, hereinbefore described. It will now also be understood that the movement of the carriage is effected step by step by means of the pawl F, operating on the ratchet c'. When the projection g' of the plate G reaches the stop 4, such plate G will be moved laterally, so that the projection underneath the pawl will raise the pawl, and it will thus be seen that the handle may be pressed laterally, so as to freely restore the carriage to the opposite side of the machine. When the projection g' reaches the stop 4', the plate G is pushed in the opposite direction, thereby throwing the projection g' closer to the pivot-point of the pawl, thus allowing it to drop preparatory to the step-by-step movement required for spacing and printing, as hereinbefore described.

On reference to Fig. 5 it will be seen that I have arranged the outer designation-ring K for the outer circle of type with the capitals and figures and the inner designation-ring for the inner circle of type with the small letters; but of course it will be understood that such arrangement is not an arbitrary one. It will also be seen that I have shown in the drawings the lever adapted to engage with the type-stems of the outer circle of type. In order to move the carriage so that the lever will engage with the inner circle, I simply throw down the thumb end of the bell-crank D', so as to bring such end underneath the pointed projection 8' of the catch 8, the catch yielding until the end d' has passed the point, when the point springs over the end D', and thereby holds it securely in position. At the same time the lower end of the pawl-crank D', engaging with the projection 8', forces forward the plate H, and consequently the rotatable disk I, until one of the type-stems of the second circle J passes to a point directly underneath the plunger M, whereupon one or more of the circle of type-letters J' may be utilized. To

restore the first circle into its proper position, it is simply necessary to pull the upper end of the catch in the direction indicated by arrow, when the spring 10 will pull upon the plate H and shift such plate and the rotatable disk I to the normal position.

I have mentioned in this specification the removable and adjustable pins n', forming the fulerum for the bars N. It will now be understood that should a different length of feed for the carriage be required—that is to say, the letters spaced a greater distance apart, as is required in case larger type is used or in certain forms of printing—such a result may be effected by shifting the pins N' so in the bars N, extending through the slots n into other holes z'. The farther away the pins are shifted from the ends N' of the bars N the greater will be the upward movement of the rod d', and consequently the greater will be the raise of the pawl, and thus when the lever is released the push of the pawl on the ratchet will be necessarily greater and the carriage moved likewise a greater distance, so as to give a greater space for the letters and in proportion.

It will be understood from this description that not only may letters be printed, but signs or words may be affixed to the type-stems. It will also be seen that my machine is adapted specially to print on flat surfaces, and although I show a platen for receiving paper from a roll it will of course be understood the platen may be utilized to receive a board for the top of a box and such board printed upon. Again, the whole frame C' may be removed and placed on a flat surface, such as the ground or table, and printing done on such surface or on anything placed thereon. It will also be seen that in the construction hereinbefore referred to the operating of the main lever serves to print the letter and move the carriage the proper space for the next letter which is being printed and also hold the rotatable disk stationary during the period that the letter is being printed.

The type-stems hereinbefore referred to are made square and extend through square holes in the rotatable disk, so as to insure of the type at the bottom being set securely for printing.

The frame C, hereinbefore referred to, is made adjustable from front to back for the purpose of spacing the distance between the lines of printing, and this is effected by means of the dog-lever C', coacting with the notches a', hereinbefore referred to.

In order to effect the spacing between words or numbers, it is simply necessary for me to turn the rotatable disk so as to bring the plunger M over the space between any two type-stems, when any suitable space may be produced between the words by the depression of the lever. The farther the lever is pushed down of course the greater the space

will be between the words, this being effected, as hereinbefore described, by the pawl F, working in the ratchet-bar c³. I may say that I have found it convenient in practice to make the ratchet-teeth twelve to the inch and that upon the operator of the machine hearing the click of the ratchet he will know the exact distance he has moved the carriage. Again, my machine is adapted to receive different disks containing different styles and size of lettering, and it is merely necessary to remove the cap 11² and the bar O', so that the lips are outside of the periphery of the disk, when such rotatable disk may be removed and another substituted.

What I claim as my invention is—

1. In a printing-machine, in combination a suitable frame provided with top end guiding-rails, a movable supplemental frame having the ends supported, so as to slide forwardly and backwardly on the guide-rails and a type-carriage laterally adjustable in the supplemental frame as and for the purpose specified.

2. In a printing-machine, in combination a suitable frame provided with top end guiding-rails, a movable supplemental frame having the ends supported, so as to slide forwardly and backwardly on the guide-rails, a type-carriage laterally adjustable in the supplemental frame and a flat platen supported underneath the type-carriage as and for the purpose specified.

3. In a printing-machine, in combination a suitable frame provided with top end guiding-rails, a movable supplemental frame having the ends supported, so as to slide forwardly and backwardly on the guide-rails, a type-carriage laterally adjustable in the supplemental frame, and a platen suitably supported on the main frame underneath the supplemental frame and means for vertically adjusting it as and for the purpose specified.

4. In a printing-machine, in combination a suitable frame provided with top end guiding-rails, a supplemental frame having the ends supported, so as to slide forwardly and backwardly on the guide-rails, a type-carriage laterally adjustable in the supplemental frame, a platen, suitable guideways in the main frame for the same, stems depending from the platen through the cross-bar of the frame, springs encircling the stems and extending between the platen and the cross-bar, and an adjusting-wheel located on the threaded end of one of the stems as and for the purpose specified.

5. In a printing-machine, in combination a suitable frame provided with top end guiding-rails, a supplemental frame having the ends supported, so as to slide forwardly and backwardly on the guide-rails, a type-carriage laterally adjustable in the supplemental frame, a platen suitably supported in the main frame and provided with longitudinal openings to form guides for the paper, a paper-roll-supporting spindle suitably journaled in the

frame, coacting spindles suitably journaled in the back of the frame and provided with feeding-rolls for the paper, and a spring-held knife designed to act against the edges of the back cross-bar of the frame, so as to sever the paper as and for the purpose specified.

6. In a printing-machine, in combination a suitable frame provided with top end guiding-rails, one of which is provided with notches, a supplemental frame having the ends supported, so as to slide forwardly and backwardly on the guide-rails, a type-carriage laterally adjustable in the supplemental frame and a spring-actuated dog operated at one end of the supplemental frame and designed to engage with the notches in one of the end guide-rails as and for the purpose specified.

7. In a printing-machine a main frame, a supplemental frame adapted to support the type-carriage within the frame and above the level of the bottom thereof so as to adapt the frame to lie on a horizontal surface, and lifting-lips for the supplemental frame to facilitate the movement to and from the horizontal surface as specified.

8. In a printing-machine a main frame, guide-rails thereon, one of said rails having notches therein, a movable supplemental frame, a dog pivotally held on the end thereof, said dog being adapted to engage with the notches in the guide-rail and a type-carriage supported by said supplemental frame.

9. In a printing-machine, a movable supplemental frame provided with grooves in the front and back thereof, of a type-carriage having a front tongue to fit in the front groove and a rear tongue to fit into the rear groove as and for the purpose specified.

10. In a printing-machine, a movable supplemental frame provided with grooves in the front and back thereof and a notch leading upwardly from the groove, of a type-carriage having a front tongue to fit in the front groove and rear tongue to fit into the rear groove, one of said tongues being narrower than the notch so as to pass therethrough as and for the purpose specified.

11. The combination with the supplemental frame and the type-carriage laterally adjustable in the same, of a ratchet-bar located at the back of the carriage, a feeding-pawl connected to the carriage, a supporting means for the pawl and means for raising such supporting means, so as to raise the pawl when the carriage has reached the limit of its feeding movement as and for the purpose specified.

12. The combination with the supplemental frame and the type-carriage laterally adjustable in the same, of a ratchet-bar located at the back of the carriage, a feeding-pawl connected to the carriage, a supporting means for the pawl, means for raising such supporting means, so as to raise the pawl when the carriage has reached the limit of its feeding movement and means for allowing the pawl

to drop when it has reached the limit of the return movement as and for the purpose specified.

13. The combination with the supplemental frame and the type-carriage laterally adjustable in the same, of a ratchet-bar located at the back of the carriage, a feeding-pawl connected to the carriage, stops located on the back bar of the supplemental frame and a laterally-adjustable plate secured to the carriage-frame and having a projection to engage with the stops and a projection to extend under the pawl as and for the purpose specified.

14. The combination with the supplemental frame and the type-carriage laterally adjustable in the same, of a ratchet-bar located at the back of the carriage, a vertically-disposed rod located in suitable bearings at the back of the carriage, a pawl pivotally connected to the bottom of the same and means for raising the rod as and for the purpose specified.

15. The combination with the supplemental frame and the type-carriage laterally adjustable in the same, of a ratchet-bar located at the back of the carriage, a vertically-disposed rod located in suitable bearings at the back of the carriage, a pawl pivotally connected to the bottom of the same, means for raising the rod and a spring for depressing the same as and for the purpose specified.

16. The combination with the supplemental frame and the type-carriage laterally adjustable in the same, of a ratchet-bar located at the back of the carriage, a vertically-disposed rod located in suitable bearings at the back of the carriage, a pawl pivotally connected to the bottom of the same, means for raising the rod, a spring for depressing the same, a slotted plate secured to the back of the carriage by pins extending through the same and having the rearwardly-extending projections, one of which extends underneath the pawl and stops toward each end of the supplemental frame with which the upper rearward-extension is designed to contact as and for the purpose specified.

17. The combination with the supplemental frame and the type-carriage laterally adjustable in the same, of ratchet mechanism located at the back of the carriage, an operating-lever pivoted on the carriage-frame and means connected to the operating-lever for raising the rod and operating the ratchet mechanism as and for the purpose specified.

18. The combination with the supplemental frame and the type-carriage laterally adjustable in the same and the rod and pawl carried by the carriage, of a ratchet-bar located at the back of the carriage, an operating-lever pivoted on the carriage-frame, means connected to the operating-lever for raising the rod and spring means for depressing it as and for the purpose specified.

19. The combination with the supplemental frame and the type-carriage laterally adjustable in the same and the rod and pawl carried

by the carriage, of a ratchet-bar located at the back of the carriage, an operating-lever pivoted on the carriage-frame, a pin extending through the rod, bars pivotally connected on each side of the lever and having the back end extending underneath the pin, and spring means for depressing the rod as and for the purpose specified.

20. The combination with the supplemental frame and the type-carriage laterally adjustable in the same and the rod and pawl carried by the carriage, of a ratchet-bar located at the back of the carriage, an operating-lever pivoted on the carriage-frame, a pin extending through the rod, bars pivotally connected on each side of the lever and having the back end extending underneath the pin, a plate located over the pin and springs designed to exert a pressure thereon to depress the rod as and for the purpose specified.

21. The combination with the supplemental frame and ratchet-bar and the carriage laterally adjustable in the supplemental frame, of the rod vertically disposed and the pawl pivotally connected to the bottom of the rod, spring means for depressing the rod, the lever suitably pivoted in front of the rod, slotted bars pivotally connected to the lever at one end and suitably connected to the rod at the opposite end and pivot-pins for the bars extending through the slots into one of a series of holes as and for the purpose specified.

22. The combination with the supplemental frame and ratchet-bar and spring-pressed rod supported in suitable bearings and a pawl pivoted in the end of the same and designed to engage with the ratchet-bar and spring means for holding the rod down, of a plate provided with a slot, a disk provided with a plurality of type-stems, an operating-lever suitably pivoted on the frame and a plunger-spring held in the raised position and designed to be depressed by the lever onto a type-stem, so as to depress it as and for the purpose specified.

23. The combination with the supplemental frame and ratchet-bar and the feeding-pawl and the operating-lever coacting with such feeding-pawl, of the type-carriage, the rotatable type-disk held thereon and carrying a circle of type-stems, the type-stems of the narrower letters being longer than the type-stems of the broader letters and a plunger designed to depress the type-stems upon it being depressed by the movement of the lever as and for the purpose specified.

24. The combination with the supporting-plate provided with a slot and the rotatable type-stem-carrying disk vertically adjustable in relation thereto, of the operating-lever and means connected thereto for depressing the type-stems one at a time through the slot in the plate as and for the purpose specified.

25. The combination with the supporting-plate provided with a slot and the rotatable

type-stem-carrying disk vertically adjustable in relation thereto, of the operating lever, means connected thereto for depressing the type-stems one at a time through the slot in the plate, an inking-pad located underneath the type-stems and means connected to the lever for depressing the rotatable disk, so as to bring the type against the pad simultaneously with the imprinting of a letter as and for the purpose specified.

26. The combination with the supporting plate provided with a slot and the rotatable type-stem-carrying disk vertically adjustable in relation thereto, of the operating lever, means connected thereto for depressing the type-stems one at a time through the slot in the plate, an inking-pad located underneath the type-stems, the pawl-carrying rod, means connected to the lever for raising it simultaneously with the depression of the type-stem, a spring held on the upper end of the rod, a double arm provided with a projection over the spring and pivoted on lugs on the frame of the type-carriage and having lips designed to extend over the rotatable type-stem-carrying disk as and for the purpose specified.

27. The combination with the carriage-frame and supporting-plate held thereon provided with a slot and the inking-pad located on the plate, of a rotatable stem-carrying disk and means for holding it depressed upon the depression of a type-stem through the slot as and for the purpose specified.

28. The combination with the carriage-frame and supporting-plate held thereon provided with a slot and the inking-pad located on the plate, of a rotatable stem-carrying disk and means for holding it depressed upon the depression of a type-stem through the slot and resilient means for holding it normally in the raised position as and for the purpose specified.

29. The combination with the carriage-frame provided with side supporting ledges or lips, of the plate provided with lugs resting on the ledges and the rotatable type-carrying disk supported on the plate, inner and outer circles of type on said disk and a spring for normally holding the outer circle of type underneath the plunger and means for forcing the plate forwardly to bring the inner circle underneath the operating-plunger and hold it there as and for the purpose specified.

30. The combination with the carriage-frame provided with side supporting ledges or lips, of the plate provided with lugs resting on the ledges and the rotatable type-carrying disk supported on the plate and a spring for normally holding the outer circle of type underneath the plunger, and a bell-crank pivoted on the standard forming part of the carriage-frame and having the lower end designed to engage with the plate and a spring-catch for holding the lower end of the bell-crank in the forward position as and for the purpose specified.

31. The combination with the carriage-frame provided with side supporting ledges or lips, of the plate provided with lugs resting on the ledges and the rotatable type-carrying disk supported on the plate, inner and outer circles of type on said disk and a spring for normally holding the outer circle of type underneath the plunger, and a bell-crank pivoted on the standard forming part of the carriage-frame and having the lower end designed to engage with the plate, a spring-held pivoted catch journaled on the standard and having a pointed lower end designed to engage with the enlarged thumb-piece of the bell-crank when it is depressed as and for the purpose specified.

32. The combination with the disk-supporting plate provided with an internal and external rim and the annular inking-pad carried thereby, and an opening or slot between the rims through which the impression is designed to be made, of the rotatable disk formed of the top and bottom plates and rim, the type-stems provided with the type-plates at the bottom thereof and spring means for holding such type-stems normally raised, a central screw-stud extending through the center of the disks into the center of the plate, and a helical spring surrounding the stud as and for the purpose specified.

33. The combination with the disk-supporting plate provided with an internal and external rim and the annular inking-pad carried thereby, and an opening or slot between the rims through which the impression is designed to be made, of the rotatable disk formed of the top and bottom plates and rim, the type-stems provided with the type-plates at the bottom thereof, spring means for holding such type-stems normally raised, a disk over the edge of the central hole of which the head of the stud extends, and a helical spring surrounding the stud and located beneath the disk as and for the purpose specified.

34. The combination with the main disk-supporting plate and the stud extending into the same and provided with an enlarged head and the rotatable type-stem disk extending around the head of the stud, of a supplemental disk extending underneath the main disk and the head of the stud and means for holding such disk normally raised against the head of the stud as and for the purpose specified.

35. The combination with the main disk-supporting plate and the stud extending into the same and provided with an enlarged head and the rotatable type-stem disk extending around the head of the stud, of a supplemental disk extending underneath the main disk and the head of the stud, means for holding such disk normally raised against the head of the stud, and an inking-pad located on the supporting-plate beneath the type-stems carried by the disk as and for the purpose specified.

36. The combination with the supporting-plate and rotatable disk-spring held above the

same, of a central stud extending through the disk into the supporting-plate and a cap fitting loosely on the top of the stud and designed to depress the disk as and for the purpose specified.

37. The combination with the rack and pawl and the rotatable plate, type-stems carried thereby, of the lever operatively connected to the pawl, the plunger located underneath the lever and so arranged that upon the depression of the plunger by the lever between the type-stems the rotatable plate is adjusted a space as and for the purpose specified.

38. The combination with the supporting-plate provided with a slot, an inking-pad located thereon and the rotating type-stem-carrying disk vertically adjustable in relation thereto and means for supporting said disk and type-stems and type normally clear of the pad.

39. The combination with the supporting-plate provided with a slot and the rotatable type-stem-carrying disk vertically adjustable in relation thereto, of the operating-lever, means connected thereto for depressing the type-stems one at a time through the slot in

the plate, an inking-pad located underneath the type-stems, the pawl-carrying rod, means connected to the lever for raising it simultaneously with the depression of the type-stem, 30 a spring held on the upper end of the rod and means connected to the lever and projecting over the disk for depressing the same, as and for the purpose specified.

40. The combination of the disk, of a double arm suitably supported and operated and provided with end bars adjustably held in the end of the arms and provided with lips extending over the rotatable disk as and for the purpose specified.

41. In a printing-machine a rotatable disk, type-stems carried thereby of different lengths and so arranged that the depression of each particular stem determines the lateral movement of the rotatable disk such a distance as 45 to properly space the corresponding letter as and for the purpose specified.
